UNITED STATES PATENT OFFICE.

JOHN W. CURRY, OF WOLFEBORO, NEW HAMPSHIRE.

IMPLEMENT FOR REMOVING NESTS OR THE LIKE.

1,197,801.

Specification of Letters Patent. Patented Sept. 12, 1916.

Application filed December 11, 1915. Serial No. 66,359.

To all whom it may concern:

Be it known that I, JOHN W. CURRY, a citizen of the United States, residing at Wolfeboro, in the county of Carroll and 5 State of New Hampshire, have invented certain new and useful Improvements in Implements for Removing Nests or the like, of which the following is a specification, reference being had to the accompanying drawings.

This invention relates to an implement for removing nests or the like and it is an object of the invention to provide a novel and improved device of this general character of a 15 portable nature and which may be manually operated with convenience and facility.

The invention consists in the details of construction and in the combination and arrangement of the several parts of my 20 proved implement whereby certain important advantages are attained and the device is rendered simpler, less expensive and otherwise more convenient and advantageous for use, all as will be hereinafter more fully set 25 forth.

The novel features of the invention will be carefully defined in the appended claims.

In order that my invention may be better understood I will now proceed to describe 30 the same with reference to the accompanying drawings, wherein—

Figure 1 is a view in front elevation with a portion in section of an implement constructed in accordance with an embodiment 35 of my invention, and Fig. 2 is a view in side elevation of the device as disclosed in Fig. 1.

As disclosed in the accompanying drawings, 1 denotes an elongated member or rod of predetermined dimensions and having 40 one extremity enlarged to form a head 1^a and secured to the opposite edges of the head are the clamping jaws A to be hereinafter more particularly described.

3 denotes an operating knob suitably secured to the lower extremity of the rod 4 disposed through the guide eyes 5 carried by the member 1 and whereby said rod 4 is capable of reciprocal movement in substantially a fixed path of travel.

50 Each of the jaws A, hereinbefore referred to, comprises a resilient shank 6 suitably anchored to the upper end of the member 1 and having its outer end provided with the head 7 preferably of substantially oval formation with its greatest diameter disposed substantially longitudinally of the member

1 and the inner face of the head is concave so that effective engagement may be had with a nest or the like.

The shanks 6 of the jaws are embraced by 60 the eyes 9 overlying the adjacent end of the elongated member or rod 1 and formed on the upper extremity of the divergent arms 10 carried by the upper end of the rod 4 and it is to be noted that the shanks 6 are bowed outwardly whereby it will be perceived that upon endwise movement being imparted to the rod 4 in one direction, the jaws A will be forced one toward the other in order to effectively clamp a nest or the like and it 65 will also be readily understood that the inherent resiliency possessed by the shanks 6 will cause the jaws A to automatically separate when the rod 4 is moved in an opposite direction whereby the nest or the like engaged or clamped between the jaws A will be released, although it will be self-evident that the shanks A will be positively caused to separate when the rod 4 is retracted.

It is to be noted that the eyes 9 are relatively spaced apart a distance less than the width of the adjacent end of the head 1^a and that the rod 4 is arranged at substantially the transverse center of the head, whereby it is assured that the heads 7 will properly coact. It is also to be noted that when the rod 4 is at the limit of its downward movement and the heads 7 consequently at the limit of separation, the heads 7 are arranged longitudinally on such relative angle as to assure 85 the outer edges of the heads to coact in such a manner as to afford a cutting action which is assured by the fact that when the rod 4 is pushed outwardly to close the heads 7, that said heads 7 will not have contact throughout their longitudinal dimension, but only 90 at the outer ends.

My present invention is particularly adapted for use in removing moth nests from trees and while I have used it with advantage for this particular purpose, I wish to be understood that my invention as herein embodied may be employed for other purposes if desired.

From the foregoing description, it is 105 thought to be obvious that an implement constructed in accordance with my invention is of an extremely simple and comparatively inexpensive nature and is particularly well adapted for use by reason of the convenience 110 and facility with which it may be assembled, and it will also be obvious that my invention

is susceptible of some change and modification without material departure from the principles and spirit thereof and for this reason I do not wish to be understood as limiting myself to the precise arrangement and formation of the several parts herein shown in carrying out my invention in practice.

What is claimed is:

- 10 An implement of the character described comprising an elongated member, having one end portion enlarged, resilient shanks secured to the opposite edges of the enlarged portion of the member and terminating in heads, each of said shanks being outwardly bowed, a rod carried by the member and capable of endwise movement, one end of said rod being provided with divergent arms terminating in eyes through which the shanks 20 are directed, said eyes overlying the adja-

cent end of the elongated member, said eyes being spaced apart a distance less than the corresponding dimension of the enlarged end of the elongated member, the rod being positioned at substantially the transverse 25 center of the enlarged portion of the member, the heads of the resilient shanks being arranged longitudinally, when at the limit of their separating movement, in such relative planes as to cause the outer ends only of 30 the heads to contact when the shanks are forced inwardly upon the outward movement of the rod.

In testimony whereof I hereunto affix my signature in the presence of two witnesses. 35

JOHN W. CURRY.

Witnesses:

CARROLL D. PIPER,
CECILE V. MARDEN.
